UNITED STATES PATENT OFFICE.

STANLEY E. BOYNTON, OF ROCHESTER, NEW YORK, ASSIGNOR TO FITZ-EMPIRE DOUBLE PIVOT LAST COMPANY, OF AUBURN, MAINE, A CORPORATION OF MAINE.

LAST-BLOCK-CENTERING MACHINE.

Application filed December 13, 1920. Serial No. 430,242.

To all whom it may concern:

Be it known that I, STANLEY E. BOYNTON, a citizen of the United States, residing at Rochester, in the county of Monroe and 5 State of New York, have invented certain Improvements in Last-Block-Centering Machines, of which the following description in connection with the accompanying drawings is a specification, like reference characters 10 acts on the drawings indicating like parts in the several figures.

This invention relates to the manufacture of lasts and in particular to gauging the rough blocks from which lasts are turned in 15 order to ascertain more closely the particular piece of work for which a given block is adapted and to preparing the block for efficient and easy use in the last lathe. The invention is disclosed in connection with a 20 preferred form of so-called last block centering jig.

Shoe lasts are turned in the copying lathe from rough blocks which may be split from the timber bolt into which the tree bole is 25 sawed, or, as is generally the case, have been already rough turned in a very heavy and rapidly cutting lathe of coarse feed. The blocks from which men's and women's lasts 30 are made come in six regular sizes, 1, 3, 5, 7, 9, and 11. These blocks are long enough to turn out a last of the indicated length with stubs $\frac{1}{2}$ to one inch long, and thick enough to produce a last of the widest width used. Obviously these blocks contain very much 35 surplus material, and it is not advisable to put the heavy work of removing it all on the last lathe, as its accuracy is impaired by the heavy vibration and springing of parts caused thereby. It is customary, therefore, 40 to trim the blocks by hand on a circular saw so as to remove much of the surplus. This operation requires much judgment and experience, as a slight error may not be discovered until after the last has been partly 45 cut and found to "run out" of the block, and a block so partially turned down can be used for a smaller last only in a few cases, since the heel dogs in the lathe are not adjustable and one last will not, therefore, 50 "nest" evenly within another, since their heel ends are in registration and the ball and cone tip of the smaller one may "run out" of the larger.

The rapidly increasing cost of last blocks

(they now cost more than three times as 55 much as before the European war, exclusive of transportation, kiln drying and storage) has made necessary far more careful procedure than has heretofore been practised. It is an important object of the present invention, therefore, to provide opportunity 60 for ascertaining definitely just how large a last can be got out of a given block, in order that waste of blocks may be avoided. It is a further important object of the invention 65 to provide dog marks in the block so related to the surface that the maximum last can be turned from the block when hung on these marks in the lathe.

Accordingly an important feature of the 70 invention consists in an organization adapted to support a model or a work piece or last block, and a feeler arranged to contact with the supported object and to indicate the excess or deficiency of the work 75 piece as regards the model. Preferably the feeler is organized in combination with a direct reading apparatus to indicate ordinary last sizes so that when the feeler has been set on the model it will indicate 80 directly the number of sizes of excess or deficiency in the block.

Another important feature of the invention resides in the provision of a block marking means for indicating the proper positioning of the block in the last lathe in order to obtain the maximum last from it as indicated by the above mentioned test. The 85 marks are preferably made to fit the ordinary lathe dogs so that the suspension of the 90 block in the lathe is rendered very simple.

Another important feature of the invention provides for grading the feelers into the positions they should assume in reference to a block or last differing in size from 95 the model. This is accomplished, in the machine shown, by moving the feeler longitudinally along the last by a slide operated by a grading lever adjustable to correspond with the length of the last.

Another feature of the invention consists in a feeler organization adapted to caliper an asymmetrical model or block, and means for reversing the feeler arrangement without loss of adjustment, to correspond to an 105 object which is the reflection of the first object caliper. The machine shown is arranged, for example, to caliper a right

model at lateral points, and to reverse the feelers to accommodate a left model of the same pair.

These and other features of the invention, including certain combinations and arrangements of parts will be understood from the following description of a preferred embodiment thereof selected for purposes of illustration and shown in the accompanying drawings in which,

Fig. 1 of the drawings is an elevation.

Fig. 2 is a plan.

Fig. 3 is an end elevation.

Fig. 4 is a detail of the model dogs.

Fig. 5 illustrates an alternative form of model and block toe dog construction.

A standard 10 supports a bed 12, having a longitudinal dovetail rib 14. A heel dog pedestal 16 is mounted on this rib. This pedestal will not normally be moved, but can be made to slide on the dovetail 14 and to be set in position by a set screw, as is well known. Once set in position, it will be very firmly clamped there. This pedestal is 20 mounted by a cap 18, hinged at 20 and fastened in closed position by the eye bolts 22. Beneath the cap in the upper end of the pedestal is a longitudinal slot 24, preferably of rectangular cross section to accommodate 30 the correspondingly shaped spindle 26, having a flange 28 to determine the position of the spindle by contact with the pedestal 16 and cover 18. The spindle has at its end a keyed taper 30 on which is mounted the 35 block heel dog 32. The taper and dog preferably correspond to the corresponding parts in the last lathe in order that the dogs may be freely interchangeable. A second spindle 34 is provided (see Fig. 4) with its 40 taper (for example) one-half inch farther out from its flange 28. This spindle is used with the model heel dog 36. The variation of one-half inch in the spindle lengths is to assure a sufficient stub length 38 in the block 45 treated as will be seen.

A second pedestal 40, similar to the first, is adjustably mounted on the dovetail 14, and provided with a set screw or clamp not shown. The toe dog spindle 42 slides freely in the slot in this pedestal and has an ordinary last lathe block toe dog 44 mounted on its end. The heel dogs 32 vary in size according to the lasts cut with them, but the toe dog 44 is always the same, and need not be freely dismountable from the spindle 42. Two spindles 42 may be provided, one (not shown) one-half inch longer than the other to be used with the model toe dog 43, or the model toe dog may be arranged to slip on 55 over the block toe dog 44 and to project one-half inch beyond it, to secure the toe stub (Fig. 5). A hardened cap 46 is placed on the end of the spindle 42 to co-operate with a second hardened cap 48 on the end of a 60 sliding rack 50, working in a pedestal 52 ar-

ranged on the dovetail 14. The rack is operated by the handles 54 keyed to a pinion in the ordinary manner. The upper side of the rack 50 carries a scale 56 co-operating with an adjustable pointer 58 mounted on the 70 pedestal 52.

Initially the model dogs are placed in position, the model grasped in them and the pointer 58 adjusted to the marked length of the last, with the rack 50 in contact with the spindle 42. That is, if the model is a 4, the pointer will be set at 4 on the scale 56, though the last may actually measure a 6, due to a pointed toe. Then after setting other parts of the apparatus not yet described, the model is removed and the block dogs inserted, as shown in Fig. 1. These dogs are, for example, each one-half inch shorter than the model dogs, which will place their tips an inch farther apart than those of the model dogs were, the points 46-48 in the block thus being in the same positions as the ends of the model, respectively.

After the block has been tested and placed on the dogs, as will be described, the rack 50 is withdrawn and then driven smartly against the spindle 42, thus driving the dogs into the block and marking it for mounting in the lathe. If the block is one inch longer than the model, the pointer 58 will read the model length on the scale 56 showing that the block is long enough for the model size with one-half inch stubs. If the block is two inches longer than the model, the pointer will read three sizes over the model size, showing that a last three sizes longer can be cut from the block, with one-half inch stubs. The maximum length of last obtainable from a given block can thus be told by mounting it in the machine.

A slide 60 is arranged to slide on the dovetail 14. This slide carries a transverse dovetail rib 64 on which slides a pedestal 66 clamped by a screw 68. At the top of this pedestal are two pins 70 on which are mounted two fingers 72, geared together at 74 and normally held closed by a spring 76. Sliding in a groove in the rib 64 are two stops 80, 82 operated by a right and left screw 84. The pedestal 66, having been set in proper position under a right model with its feelers 90 (described below) in contact with the sides of the model will be somewhat "off center" on the rib 14, due to the asymmetry of the last. Now if the stops 80, 82 are set up until one of them contacts with the pedestal, the pedestal can be set properly for a left model or last by merely sliding it over to contact with the other stop, which is just as far to the other side of the line of centers of the rib 14. The slide 60 is not clamped to the rib 14, but is normally movable for grading purposes, as will be described.

A pointer 86 is set screwed to a pin 70, and a scale 88 is mounted on a finger 72 to co-operate with it. When a model has been placed in the machine and the slide 66 5 adjusted so that the feelers 90, mounted on the fingers 72 and vertically adjustable as at 91, just contact with its ball portion on both sides, the pointer 86 may be set to read as desired on the scale. (For practical purposes it is regarded as desirable that the block be one-fourth inch oversize everywhere. That means that it will be about six sizes "wider" than the last cut from it. The scale 88 is preferably graduated so that 10 its unit represents the finger movement, due to a change of one width size in the model grasped. The pointer will therefore be set at -6 on the scale.) When the model is removed and the block inserted and the 15 feelers 90 brought up to it, the pointer will thus read directly the maximum last ball that can be cut from it on this one-fourth inch oversize assumption.

The slide 60 also carries pedestal 92 in 20 which is mounted a pin 94, into which is threaded a screw 96 with a contact point 98, and operable by a knurled head. The pin 94 rests on a wedge 102 which runs through a slot in the bottom of the pedestal 92, and is 25 held in adjusted position by a screw 104. The end of the wedge reads on a graduated scale 106. This scale has the same significance as the scale 88 already discussed. When the model has been inserted the wedge 30 will be set to read -6 and the knurl turned to place the feeler 98 in contact with the bottom of the ball. The wedge is then pulled out and the block inserted. When the wedge is replaced and slid in until the 35 feeler 98 touches the bottom of the block the end of the wedge will read directly the maximum last ball bottom which can be cut from the block in this position on the dogs, upon the one-fourth inch oversize assumption. 40

Another slide 108 is mounted on the rib 14 under the heel portion of the last, and may be clamped in position by a screw 110. Its feelers 112 are not shown as vertically 45 adjustable. Otherwise the construction is entirely similar to that of the slide 60 and its associated parts and its description need not be repeated here.

At the rear of the machine a column 112 50 is mounted on the base 12. This column carries a vertical dovetail rib 114, upon which slides a slide 116, operated by a lever 118, pivoted at 120 on the column 112, and a treadle not shown. The slide 116 carries a 55 forwardly extending U-shaped arm 120^a, the arms of the U having several pairs of aligning slots 122, in each of which pairs of slots slides a rack 124. The middle of the U carries an arm 126, provided with 60 corresponding slots 125. The bottoms of

the arm 126 and of the right hand U arm are slotted as shown at 128 and bars 130 are fastened in the slots. Four racks 124 and bars 130 are shown, but the number 65 may be varied as desired.

The bars 130 serve as guides for the slides 132, which are all alike, and are mounted one on each bar 130 and held in adjusted position by a set screw 134. The slides each contain a vertical slideway in which works 70 a rack 136 engaging a pinion 138 on an axis 140 in the slide 132. The slides 132 contain also a second horizontal slideway in which the racks 124 slide in co-operation with the 75 pinions 138.

The slide 116 carries a bracket 142 on which is pivoted a gridiron-shaped grading lever 144 shown as composed of six parallel bars 146 united in a gridiron by a bolt 148, suitable spreader pieces 150 and a pivot bolt 152, hinging the lever to the bracket 142. Four of the bars 146 carry each a slide 154 80 held in adjustable position by a set screw 156. This slide carries a pin 158 extending laterally from it and working pivotally 85 in a slot 160 in the top of one of the racks 136. Swinging movement of the lever 146 will thus raise or lower the racks 136 and operate the racks 124.

The pin 158 associated with the left hand 90 bar 146 (Fig. 3) works in a slot in a graduated vertical slide 162 which works in a slide 164 which runs on a graduated horizontal bar 166, fastened to a bracket 168 bolted to the slide 116. The graduations of 95 the bar 166 and slide 164 are the ordinary shoe size graduation of one-third inch per size and the parts are so proportioned that the distance from the end 167 of the scale on 166 to the reading point 169 equals the 100 distance from the pivot 152 to the pin 158 on the bar 162. The graduation on the bar 162 reads zero when the lever is horizontal, 105 as shown.

The pin 158 associated with the right hand bar 146 (Fig. 3) is simply pivoted to a link 170, the lower end of which is pivoted to a pin 172 arranged to be clamped in a slot 174 in the rack 176 by a wing nut 178 without affecting the pivotal relation between the pin and the link 170. The rack 176 operates a pinion 180 in a slide 182 in a vertical guide in which works the rack 176 and which is adjustable along the bed 12 by a slideway and set screw 184. The 110 pinion 180 operates a rack 186 which is pivoted at its end to the slide 60 at 188.

The ends of the racks 124 each carry a fixed frame 190 in which works a vertical slide 192 with a feeler 193 at its lower end and having a pin 194 in a cam slot 196 in a lever 198 pivoted at 200 on the frame 190. The lever 198 is arc-shaped and carries a movable scale 202 on its periphery, and a pointer 204 is fixed to the frame 190 in co- 125 130

operation with the scale. The horizontal distance between each feeler 193 and its associated pin 158 is uniform and equal to the distance of the feeler 98 on the slide 60 from its pin 158. The scale 202 and cam slot 196 are so related that a scale interval corresponds to the movement of a feeler 193 corresponding to an increase of one size in width in a last suspended on the dogs, and the graduation of the scale is preferably arranged as an equicrescent one, the slot being so shaped as to cause the proper movement of the feeler 193 at any distance from the axis of centers.

When the model has been set in the machine, the feelers 193 and the slide 60 are adjusted to the desired positions along the model by loosening the set screw 68, 184, 134, 156, the lever 144 being horizontal. The slide 164 is also adjusted to read the actual measured length of the model on the scale 166. The feelers 193 will be brought down to the model by rotating the levers 198 and the scales 202 will be set at -6 on the pointers 204. All the set screws will be tightened. When the block is inserted the lever 144 will be moved so that the scale on the bar 162 reads the excess or deficiency in length as compared with the model of the proposed last to be cut from the block. This will move the racks 136 and 124 to move the fingers 204 and the slide 108 to the positions into which they should "grade" in order to reach the points on the block which correspond to the contact points of the model. For example, if the last is to be two sizes longer than the model, the end of the grading lever will be lowered two-thirds inch as shown by the scale on the slide 162. All the racks 124 will then be moved to the right in Fig. 1 by the fractional parts of two-thirds inch which the distances of the corresponding feelers from the heel end of the model are of the total model length. The heels of all models and lasts come to the same point 46, which has the same longitudinal geometrical relation to the points on the last in front of it as the pivot 152 has to the bars 136 when they are in position to place the feelers 193 over the said points on the last, respectively. The mechanism being thus set, the scales 202 will indicate directly the maximum one-fourth inch oversize last which can be cut from the block in the vicinities of their associated feelers 204.

It is not necessary to grade the slide 108, since its movement would be so small, and the whole operation when carried out on a rough last block is not a delicate one any way.

The foot treadle and lever 118 will be used after loosening the nut 178 to raise the feelers 204 and all their associated mechanism well out of the way when the model is being removed and the block inserted.

In practice, the operator will endeavor to position the block in the dogs so as to obtain from it a certain last, and then drive in the dogs, rather than put the block in the dogs without regard for other considerations. The preceding explanation, for the sake of simplicity, has tacitly assumed that the block is in position and that the feelers will then tell what can be done with it at different points, whereas the actual procedure is somewhat different, as just mentioned.

Having thus described my invention, what I claim as new and desire to secure by Letters Patent of the United States is:—

1. A centering machine having dogs for engaging the work, and an alternate set of dogs for engaging the model, the dog supporting means being constructed and arranged to hold the model dogs within the positions occupied by the work dogs, to provide for adequate stubs on the work.

2. A centering machine having dogs for engaging a work piece, one of said dogs being movable to accommodate work of varying sizes, and to indicate directly the length of the last corresponding to a given model which can be cut from the work piece.

3. A work gaging machine arranged to support a model or a work piece, and having a feeler arranged to contact with the surface of the object held in the machine and to indicate the excess or deficiency of the work piece as regards the model.

4. A work gaging machine arranged to support a model or a work piece, and having a feeler arranged to be moved along the object held in the machine to contact with its surface at a desired point and to indicate the excess or deficiency of the work piece as regards the model.

5. A work gaging machine arranged to hold a model or work piece in corresponding positions, a feeler projectable to touch the lateral surface of the model or work piece, and means for directly reading the excess or deficiency of the work piece at the point of contact, as regards the model.

6. A gaging machine arranged to hold a model or a work piece in corresponding positions, having a feeler movable to touch the surface of the model or work piece in corresponding points, and means comprising a cam and a scale for moving the feeler and indicating the excess or deficiency of the work piece over the model at the contact point.

7. A machine of the class described, arranged to hold a model or a work piece in corresponding positions, having a feeler movable laterally of the model or work piece to contact with the model or work piece in corresponding points, and movable also longitudinally of the model or work piece to reach different localities thereon, and a

direct reading apparatus for indicating the excess or deficiency of the work piece over the model at the point of contact.

8. A machine of the class described, arranged to hold a model or a work piece in corresponding positions, having a feeler movable laterally of the model or work piece to contact with the model or work piece in corresponding points, and movable also longitudinally of the model or work piece to reach different localities thereon, the feeler being organized for directly indicating the excess or deficiency of the work piece over the model at the point of contact, and mechanism for longitudinally grading the feeler into the same position regarding the work piece as it occupies regarding the model.

9. In a machine of the class described, arranged to hold a model or a work piece in corresponding positions, a feeler movable laterally of the model or work piece to contact with the model or work piece in corresponding points, and movable also longitudinally of the model or work piece to reach different localities thereon, and a scale for indicating the excess or deficiency of the work piece over the model at the point of contact, and mechanism for longitudinally grading the feeler into the same position regarding the work piece as it occupies regarding the model, comprising a pivoted lever and a connection between the feeler and the lever whereby the feeler is moved longitudinally of the work piece by movement of the lever.

10. In a gaging machine arranged to hold a model and work piece in corresponding positions, a feeler movable along the object held to reach a desired feature thereof, a grading lever and a connection between the lever and the feeler whereby the feeler is moved by the lever into corresponding positions in respect to the model and work piece.

11. A gaging machine arranged to hold a model and work piece in corresponding positions, having a feeler movable along the object held to reach a desired feature thereof, a grading lever and a connection adjustable along the lever in correspondence to the adjustment of the feeler along the object and running between the lever and the feeler whereby the feeler is moved by the lever into corresponding positions in respect to the model and work piece.

55 12. A machine of the class described arranged to hold a model and work piece in corresponding positions, having a feeler movable along the object held to reach a desired feature thereof, and a grading lever and a connection of invariable effective length adjustable along the lever in correspondence to the adjustment of the feeler along the object and running between the lever and the feeler whereby the feeler is moved by the lever into corresponding posi-

tions in respect to the model and work piece.

13. In a machine of the class described, arranged to hold a model and a work piece in corresponding positions, a slide movable along the object held and carrying a laterally movable feeler, a grading lever, a member adjustable along the lever, and a connection between the member and the slide whereby their corresponding movements due to the adjustment are proportional.

14. In a machine of the class described, arranged to hold a model and a work piece in corresponding positions, a slide movable along the object held and carrying a laterally movable feeler, a grading lever, the effective length of which is adjustable to correspond to the model length, a member adjustable along the lever and a connection between the member and the slide, whereby the member and feeler may be placed in similar relation to the lever and model respectively and whereby also movement of the lever on its pivot corresponding to the excess or deficiency in length of a work piece over the model will grade the feeler into the same geometric position along the work piece.

15. A machine of the class described having feelers arranged to contact with the opposite sides of a model, and means for moving the feeler organization on one side out of operative relation to the model to facilitate removal of the model and substitution of an oversize block.

16. A machine of the class described, arranged to hold a model last or a last block in corresponding positions, having caliper members geared together for equal opposite movements and arranged to engage the opposite sides of the model or block and two stops for positioning the entire caliper organization for rights and lefts respectively.

17. A machine of the class described, arranged to hold a model last or a last block in corresponding positions, having caliper members arranged to engage the opposite sides of the model or block and two stops for positioning the entire caliper organization for rights and lefts respectively.

18. A machine of the class described, arranged to hold a model last or a last block in corresponding positions, having caliper members arranged to engage the opposite sides of the model or block and two stops geared together by a right and left screw for positioning the entire caliper organization for rights and lefts respectively.

19. A machine of the class described, arranged to hold a model last or a last block in corresponding positions, having caliper members geared together for equal opposite movements and arranged to engage the opposite sides of the model or block and arranged to slide laterally together to contact with rights and lefts as desired and two stops for positioning the entire caliper or-

ganization for rights and lefts respectively.

20. A block centering machine having a feeler arranged to contact with the surface of a model and work piece in turn, and to indicate the excess or deficiency of one over the other, and means for marking the work piece while held in the contacting position whereby the work piece may be supported in proper position in the machine which is to operate upon it.

21. A block centering machine having means for impressing jig-marks on a last block, and a feeler arranged to contact in predetermined relation to said means with a model and last block similarly placed in the machine and to indicate the excess or deficiency of one over the other.

22. A block centering machine having means for similarly gaging a model and last block to indicate the excess or deficiency of one over the other, and means for impressing dog marks in the block whereby it may be suspended in a last lathe.

23. A block centering machine having means for similarly gaging a model and last block to indicate the excess or deficiency of one over the other, and means for impressing dog marks in the block whereby it may be suspended in a last lathe, said marks occupying the same position relatively to the gaged points in the block as the corresponding model dog marks do to the corresponding gage points of the model.

24. A block centering machine having ordinary last lathe model dogs for supporting a model and provided with last lathe block dogs whereby a block may be similarly supported and feelers arranged to contact

with a said supported object to indicate excess or deficiency of one over the other, the block dogs being relatively movable to impress dog marks in the block whereby it may be hung in the last lathe.

25. A block centering machine having means for engaging last lathe dog marks in a model or block, and a feeler arranged to engage the model or block at a desired point and directly indicating the excess or deficiency at the point of the one over the other.

26. A block centering machine having means for engaging last lathe dog marks in a model or block, and a feeler arranged to engage the model or block at a desired point and directly indicating the excess or deficiency at the point of the one over the other, the engaging means being movable to impress marks in the block.

27. A last block centering machine having two interchangeable dog-systems arranged to hold and mark a model and block respectively, the model and block dogs corresponding to the same end of the model and block differing in length by the desired block-stub-length.

28. A last block centering machine having dogs movable to mark a last block for engagement with a last lathe, in combination with a feeler movable to engage a block suspended on said dogs and to indicate directly the excess or deficiency thereof over a model last.

In testimony whereof I have signed my name to this specification.

STANLEY E. BOYNTON.
